UNITED STATES PATENT OFFICE.

GERTRUDE M. KREMERBERG, OF PITTSFIELD, MASSACHUSETTS.

WATER-COOLING DEVICE.

1,268,362.

Specification of Letters Patent. Patented June 4, 1913.

Original application filed August 14, 1912, Serial No. 715,017. Divided and this application filed April 17, 1914. Serial No. 332,423.

To all whom it may concern:

Be it known that I, GERTRUDE M. KREMERBERG, a citizen of the United States, and resident of Pittsfield, in the county of Berkshire and State of Massachusetts, have invented certain new and useful Improvements in Water-Cooling Devices, of which the following is a specification.

My invention relates in general to a water cooling device and particularly relates to such a device forming part of a system for sterilizing drinking water and other potable liquids. This application forms a division of my co-pending application for water systems, Serial No. 715017, filed August 14, 1912.

One of the objects of the invention is to provide an economical means for rapidly cooling liquids for drinking and other purposes, which liquids have been previously subjected to a boiling, sterilizing or similar heating treatment.

Another object is to provide a means for subjecting the liquid to a two stage cooling operation and to provide means for regulating the admission of the fluid from one cooling device to the other, operatively dependent upon the amount of liquid in the device.

Still another object of the invention is to provide a cooling means, which may be continuously open to a constant source of liquid supply and which will maintain but a limited amount of the liquid under the influence of the cooling medium.

Various other objects and advantages of the invention will be in part obvious from an inspection of the accompanying drawings and in part will be more fully set forth in the following description of one form of mechanism embodying the invention, and the invention further consists in certain new and novel features of construction and combination of parts hereinafter set forth and claimed.

Referring to the accompanying drawings:

Figure 1 is a vertical central sectional view of an ice tank and pipe connections disclosing a preferred embodiment of my invention;

Fig. 2 is a fragmental horizontal sectional view of the ice tank on the line $w-w$ of Fig. 1 with some of the parts omitted, and

Fig. 3 is a longitudinal vertical central sectional view of the valve mechanism regu-

lating the circulation of water for the cooler.

In the apparatus illustrated, the sterilized water, or other liquid to be cooled, is given a preliminary cooling by contact with a circulating cooling medium, such as water direct from the street mains, before it is fed to the ice box and for this purpose there is provided a cooler shown fragmentary at 56, which includes an inner coil 57 adapted to be connected at its lower end to a boiler, sterilizer or other suitable heating device for treating the liquid. The coil is incased in a receptacle 59, which is connected to some suitable source of cooling medium, such as the street mains. The cooler is also tapped to receive an outlet pipe 62, which is provided with a valve 64. The flow through this pipe is automatically controlled as will later be described. The upper end of the coil 57 is connected to a pipe 65 having a valve 67 for controlling the flow of liquid therethrough. The pipe 65 is connected with the ice box 76 for supplying the same with the treated liquid by automatically controlled means as will later be described.

This ice box comprises an outer double wall 89 having a suitable non-conducting filler, and a cover 90 similarly constructed. Within the box is an inner chamber 91 for containing the liquid, which converges toward the bottom to form a funnel which connects with one end of a coil 92. The other end of the coil is connected with the supply faucet 79 by means of which the cooled liquid is drawn as described.

The receptacle has an overflow pipe 77, which dips in a trap 78, the liquid finally overflowing from the trap into some suitable receptacle. Two ice receptacles 93-93 are placed between the chamber 91 and side walls 89, and are of suitable size to form a space 94 between them. The pipe 65 enters the ice tank and passes through the space 94 to the chamber 91. The pipe is connected with a valve 95 automatically controlled by the float 96.

A spray pipe 97 extends from the valve 95 and throws the liquid upon a filter 98. The circulation pipe 62 is controlled by the rise and fall of the liquid in the chamber 91.

The pipe 62 is connected with a pipe 99, which extends through the space 94 into the chamber 91. This pipe has an inner

pipe 100 passing through it and is in communication with it at its inner end where a valve seat 101 is formed. This is adapted to engage with a valve 102. A valve stem 103 connected to the valve 102 extends through the pipe 99 and 100 and acts on the valve to move the same to and from its seat by means of the float 104, which operates in the usual way with the rise and fall 10 of the water in the receptacle 91. The opposite end of the pipe 100 extends through the pipe 99 and is connected to a pipe 105, which conveys the circulation water therefrom to the sewer or other suitable drain. 15 In operation, the liquid is treated by some suitable heating process and conveyed to the cooler 56, and from there through the pipe 65 to the ice box 76, but is held in check by the float controlled valve 95, 20 until the liquid in the chamber 91 of the ice box is drawn off. This lowers the surface of the water in the tank, thereby lowering the float 96. The valve 95 is thereby opened and the liquid permitted to flow through 25 the orifices in the pipe 97 until the float 96 rises sufficiently with the rising of the water to again close the valve 95. The circulating water for the cooler 56 passes therefrom through the pipe 62 to 30 the pipe 99 where it is checked by the valve 102 when the water in the chamber 91 is sufficiently high to close the valve. When the water is drawn from the chamber 91, the float 104 drops and opens the valve. 35 The circulating water in pipe 99 then flows into the pipe 100 and from here it flows into the pipe 105 and empties into the sewer. The cooling water for the cooler 56 therefore only flows when the liquid in the 40 chamber 91 is being withdrawn through the faucet 79, at which time the valve 95 is automatically opened by the dropping of the float 96 and a further supply of liquid is permitted to flow through the coil 57 at 45 the same time cooling water is permitted to flow about the coil as just described.

By means of a device of this character, the liquid is cooled with an economical use of ice for the hot or warm liquid is given 50 a preliminary cooling as it passes through the water jacketed cooler, which quickly lowers the temperature substantially to that of the water from the street mains.

Further the spraying action of the pipe 55 97 has the effect of opening the body of liquid thereby facilitating the absorption of the heat therefrom by the ice in the outer compartment. The body of the liquid is gradually reduced in cross-section by means 60 of the funnel shaped bottom thus bringing smaller and smaller volumes of the liquid under the influence of the cold bottom portion of the ice box and the liquid is then directed into the small bored coils directly 65 under the ice receptacles.

The automatically controlled valves limit the amount of liquid admitted to the ice box so that the ice is not used in maintaining a large mass of the liquid at abnormal temperatures and at the same time, the device 70 is always open to a fresh supply of liquid.

Further by means of the float control valve the circulating water for the cooler is conserved and flows only when a fresh supply of the liquid is being fed to the 75 ice box.

While I have shown and described, and have pointed out in the annexed claims, certain novel features of my invention, it will be understood that various omissions, 80 substitutions and changes in the form and details of the device illustrated and in its operation may be made by those skilled in the art without departing from the spirit of the invention.

Having thus described my invention, what I claim and desire to protect by United States Letters Patent is:

1. An ice box of cylindrical form having heat insulating walls, an inner compartment 90 and an outer compartment surrounding said inner compartment and adapted to contain a plurality of removable ice containing receptacles, a funnel forming the bottom of said inner compartment, coils disposed in 95 said outer compartment adjacent the bottom thereof, positioned below the ice receptacles and leading from said funnel, a filter covering the opening to said funnel, a spraying device above said filter, a conduit leading to 100 said inner compartment, a valve controlling the passage of liquid through said conduit, a float in said inner compartment operatively connected to said valve to shut off the supply of liquid to said spraying device 10 when the liquid in the inner chamber has reached a definite level.

2. A device for cooling liquid in two stages, comprising a cooler having a circulating cooling medium therefor adapted to 11 give the liquid a preliminary cooling, an ice box spaced from the cooler, a connection for conveying the partially cooled liquid from the cooler to said ice box for a further cooling and means controlled by the liquid level 11 in said ice box for regulating the admission of the liquid to said ice box and means also controlled by the liquid level in said ice box for regulating the cooling medium in the cooler and operating on a rise of liquid 12 in cooled liquid in the ice box to intercept the flow of the cooling medium through the cooler.

3. A device for cooling liquid in two stages, comprising a cooler having a circulating cooling medium therefor adapted to give the liquid a preliminary cooling, an ice box constituting a device distinct from the cooler and spaced therefrom, a connection for conveying the partially cooled liquid from the 1

- cooler to said ice box for a further cooling, valvular means controlled by the liquid level in said ice box for regulating the passage of the cooling medium through said cooler.
- 5 4. An open top ice box having heat insulated walls and having an inner liquid containing compartment, and an outer compartment adapted to contain a plurality of removable ice receptacles, means for leading liquid to said inner compartment through a side thereof, a cover for the upper end of said inner compartment, a funnel forming the bottom of said inner compartment, a cooling coil positioned adjacent the bottom 10 of said outer compartment and below said funnel and ice receptacle connected to receive the liquid from said funnel and means for drawing the cooled liquid from said coil.
- 15 5. In a device of the class described, a receptacle, designed to receive a liquid, means for supplying liquid to said receptacle, means for cooling said liquid, and float controlled means in said receptacle for simultaneously intercepting the operation of said supply 20 means and said cooling means, said float controlled means operable on a raise from a predetermined level of the liquid in said receptacle whereby the level in the receptacle controls the duration of both the inflowing 25 liquid and the cooling operation.
- 30 6. In a device of the class described, a receptacle, designed to receive a limited quantity of liquid, means including a normally open conduit conducting a fluid therethrough for cooling said liquid prior to its introduc-
- tion into said receptacle and means controlled by the raise in level of liquid in said receptacle for intercepting the free flow of the cooling liquid through said cooling means.
- 40 7. In a device of the class described, a receptacle, designed to receive a limited quantity of liquid, means spaced from the receptacle for cooling said liquid prior to its introduction into said receptacle, a conduit connecting said means with said receptacle and means within the conduit and controlled by the raise in level of liquid in said receptacle for inaugurating the action of said cooling means and means for preventing an abnormal rise of level of the liquid in said receptacle.
- 45 8. In a device of the class described, a receptacle designed to receive a quantity of liquid, a conduit for supplying the liquid to said receptacle, a water conduit for cooling said liquid, a pair of floats in said receptacle actuated by a change in level of the liquid in the receptacle, one of said floats controlling the admission of the liquid to said receptacle and the other float controlling the water cooling conduit.
- 50 Signed at Pittsfield, in the county of Berkshire and State of Massachusetts, this fifteenth day of April, A. D., 1914.
- 55 GERTRUDE M. KREMELBERG.
